UNITED STATES PATENT OFFICE.

JENS BRODERSEN HIORTH, OF HOVIK, NEAR OSLO, NORWAY.

GUIDE APPARATUS FOR THE PROPELLER STREAM OF VESSELS.

Application filed September 22, 1927, Serial No. 221,246, and in Norway September 28, 1926.

Prior to the present invention it has been suggested in connection with vessels driven by one or more screw propellers to attach 5 guide vanes for the propeller stream to the rudder post or, where balanced rudders are used, in connection with the same, in order to direct the propeller stream into an axial flow. Where the guide vane is attached to the rudder post it has been suggested fur- 10 ther to construct the guide vane and the forward edge of the rudder with such thickness that their surfaces are flush with the pivot eyes of the rudder or overlap the same so that guide vane, rudder post and rudder 15 together form a body with continuous smooth surfaces, thereby avoiding eddying between rudder post and rudder with a view to improving the rudder action as well as the efficiency of the propeller.

20 Heretofore, in most constructions of this kind, the guide vane has been arranged symmetrically to the vertical plane through the center line of the propeller shaft. It has, however, also been suggested where 25 there was the question of application of guide apparatus for the propeller stream to existing vessels, to fix the guide vane at the side of the rudder post and thus somewhat asymmetrically to the vertical plane through 30 the center line or axis of the propeller shaft. In these known constructions the rudder always has been constructed symmetrically to the said plane, whereby, owing to the 35 asymmetrical fitting of the guide vanes, the flowing of the water to both sides of the rudder was unequal, which gave a reduced 40 efficiency of the propeller and a reduced effect of the rudder. Furthermore it was always necessary to locate the forward or 45 leading edge of the guide vane considerably out of the vertical plane through the center line of the propeller shaft which, as experience shows, is unfavourable to the efficiency of the guide apparatus.

50 According to this invention the aforesaid defects are avoided in that the center line of the horizontal section of the rudder is arranged asymmetrically to the axis of rotation of the rudder which is situated in the vertical plane through the center line of the propeller shaft, in order to obtain equal flow of the water to both sides of the rudder, with an asymmetry equal to or approximately equal to the asymmetry of the guide 55 vane. Furthermore according to the present

invention the forward or leading edge of the guide vane is located in or approximately in the plane through the center line of the propeller shaft, the shape of the guide vane and its asymmetry thereafter being determined with a view to obtaining the most favourable passage of the stream lines at the deflection of the propeller stream.

The center line of the rudder section may be straight or curved and the surfaces of 60 the rudder also may be straight or curved. If the rudder and the guide vane are constructed with the same thickness so as to form together a body with continuous, 65 smooth surfaces, then this body will, because of its asymmetry, already in the midship position of the rudder have a vane- or shovel form cross section whereby, besides an improvement in the efficiency of the propeller, a steering action is obtained with the 70 rudder in midship position, and by turning of the rudder a considerably greater side pressure is obtained than at the same turning of the usual rudder, i. e., a shorter turning 75 of the rudder is necessary for obtaining of 80 the desired rudder action. At the same time by suitable shaping the rudder section the center of pressure of the water can be brought comparatively near to the axis of 85 turning of the rudder and displacement of the center of pressure during turning of the rudder is reduced to a minimum.

Some embodiments of my invention are illustrated in the accompanying drawing in which all figures show horizontal sections 90 through guide vane and rudder.

Fig. 1 shows an arrangement with the guide vane 1 attached asymmetrically to the rudder post 2, and with asymmetrically formed rudder 3, the cross section of which 95 has a straight center line. Fig. 2 shows a similar arrangement, only in that the rudder 3 is formed as a vane or shovel with concavity a-port. In both these embodiments the guide vane and rudder are constructed 100 of plates and angles, suitable for mounting on an existing structure. For new constructions the rudder post and rudder frame, of course, may beforehand be given the form most suitable for the construction.

Fig. 3 shows an asymmetrically formed balanced rudder 4, the forward edge of which forms a guide vane 5. 6 is the pivot axis of the rudder. Fig. 4 also shows a balanced 105 rudder 4, provided with guide vane 5, the 110

rudder being given the form of a vane with stronger curve and concavity a-port. In this figure also 6 is the pivot axis of the rudder.

5 Having now particularly described and ascertained the nature of my said invention and in what manner the same is to be performed, I declare that what I claim is:

1. In combination a ship's rudder, a guide 10 vane for the propeller stream attached to the rudder post asymmetrically to the vertical plane through the center line of the propeller shaft, the rudder being of the stream line type and having the axis of its pivots 15 arranged off the median line through the horizontal section of the rudder with an asymmetry approximately corresponding to the asymmetry of the guide vane.

2. In combination a balanced ship's rudder

der of the stream line type, a guide vane for 20 the propeller stream rigid therewith, the axis of the pivots of the rudder being arranged off the median line through the horizontal section of the rudder.

3. In combination a ship's rudder, a guide 25 vane arranged asymmetrically to the vertical plane through the axis of the propeller shaft, the axis of the pivots of the rudder being arranged off the median line through 30 the horizontal section of the rudder with an asymmetry approximately corresponding to the asymmetry of the guide vane, and the forward edge of the guide vane being situated approximately in the said plane 35 through the axis of the propeller shaft.

In testimony whereof I hereunto affix my signature.

JENS B. HIORTH.
